UNITED STATES PATENT OFFICE.

REUBEN C. ELDRIDGE, OF NIAGARA FALLS, ONTARIO, CANADA, AND JULIUS WILLERS, OF NIAGARA FALLS, NEW YORK, ASSIGNORS TO NIAGARA FALLS METAL STAMPING WORKS, OF NIAGARA FALLS, NEW YORK.

HAME-FASTENER.

No. 863,162.

Specification of Letters Patent.

Patented Aug. 13, 1907.

Application filed May 18, 1906. Serial No. 317,508.

To all whom it may concern:

Be it known that we, REUBEN C. ELDRIDGE, a subject of the King of Great Britain, residing at Niagara Falls, in the Province of Ontario, Canada, and JULIUS 5 WILLERS, a citizen of the United States, residing at Niagara Falls, in the county of Niagara and State of New York, have invented a new and useful Improvement in Hame-Fasteners, of which the following is a specification.

10 This invention relates more particularly to that kind of adjustable fasteners for harness hames which comprise a chain connected to the end of one hame and a buckle or catch attached to the end of the other hame and which enables the chain to be drawn taut and 15 holds it when adjusted.

The primary object of the invention is to produce a very strong, durable and efficient hame fastener of neat appearance which can be manufactured economically and which will operate smoothly and easily in adjusting and fastening and loosening the hames.

More specific objects of the invention are to provide the chain catch or buckle with a pivoted tongue of novel shape formed from sheet metal, which has great strength for the size and amount of metal; to secure the 25 tongue operating spring to the tongue in such manner that it will be inclosed, protected and hidden; to provide the chain catch or buckle with a cross bar over which the chain runs, which by reason of its peculiar shape in conjunction with the shape of the chain links 30 insures a free and easy movement of the chain over the same in the use of the fastener; and to so form, arrange and construct the parts of the hame fastener that a superior article can be manufactured at a reduced cost from sheet metal, by die and press operations.

35 In the accompanying drawings: Figure 1 is an elevation of the lower ends of a pair of hames connected by a fastener embodying the invention. Fig. 2 is a perspective view, partly broken away, of the buckle or catch. Fig. 3 is a plan view of the buckle or catch tongue detached. Fig. 4 is a sectional elevation of the 40 buckle or catch and a portion of the chain. Fig. 5 is a cross sectional elevation of the chain and cross bar of the buckle or catch. Fig. 6 is a perspective view of one of the chain links detached. Fig. 7 is a perspective view of the chain hook. Fig. 8 is a plan view of the chain hook before completion. Fig. 9 is a cross section of the chain hook in line 9—9, Fig. 8.

Like letters of reference refer to like parts in the several figures.

45 A A¹ represent the lower portions of a pair of hames of ordinary construction provided with loops or eyes a¹ at their lower ends. A chain B is removably connected by a hook C at one end thereof to the loop a of one hame, and has an adjustable engagement with a

buckle or catch D removably connected to the loop a¹ 55 of the other hame for the purpose of adjusting the hames on the collar. The chain B is preferably of that kind composed of permanently connected folded or doubled sheet metal links, in which each link (see Fig. 6) has at one end two superposed eyes e and at the 60 opposite end a loop e¹ at right angles to the width of the link to receive the two eyes of the next link. The construction of the chain is not new, but attention is directed to the fact that the loop ends of the links are 65 relatively narrow and thick, while the eye-ends are relatively flat and wide and taper toward the loop ends, i. e. they are of substantially triangular form.

The hook C for removably connecting the chain to the hame loop a is made of sheet metal from a blank f of substantially the oval shape shown in Fig. 8, and 70 this blank is made with a longitudinal rib or bulge f¹ which extends around the bend of the completed hook and adds greatly to the strength and stiffness thereof. The hook C is joined to the chain by a loop or strap g which passes through the two eyes e of the end link 75 of the chain and has both ends thereof rigidly secured to the hook by a rivet g¹, see Figs. 1, 7 and 8. As the eyes of the chain link are not split or capable of being opened, the hook loop is engaged in the link eyes while its ends are disconnected and the hook blank f is then 80 placed between and riveted to the two ends of the loop. The loop and hook are thus riveted together and the stiffening rib f¹ formed in the hook blank in a single press operation with suitable dies, and in joining the parts in this way the ends of the loop are pressed into 85 conformity with the end and ribbed portion of the hook blank, see Fig. 9, and a rigid and very strong connection is secured at small cost.

The catch or buckle D consists of a body h and a 90 spring actuated tongue pivoted thereto. The body of the catch is made of sheet metal formed by pressing, or otherwise, into substantially inverted U-shape in cross section, having spaced sides connected by a top or back. The top is extended at one end and bent to form a hook h¹ for detachably engaging in the loop of 95 one hame, the hook being preferably strengthened and stiffened by a convexed longitudinal rib h² extending around the bend of the hook. The sides of the body at the opposite end of the catch extend beyond the top and are connected by a cross bar or part i over 100 which the chain passes between the projecting ends of the sides. The cross bar or part is of spool shape, see Figs. 2 and 5, having oppositely flaring or frusto-conical ends i¹ joined by a reduced cylindrical central or waist portion, and preferably consists of a sleeve pressed 105 or otherwise formed from a sheet metal blank and surrounding a rivet i² which extends through holes in the sides of the catch body with its ends headed down to

hold the parts together. The sleeve could be loose on the rivet so as to turn thereon as a roller, but it is preferably compressed about the rivet and clamped between the sides of the catch body so as to be rigidly held and to brace the sides. In pulling on the chain, to tighten or adjust the hames, it runs very smoothly and freely over the cross bar on account of the described shape of the chain links and cross bar. The thick loop ends of the links slide on the reduced waist 5 of the cross bar, while the diverging sides of the eye ends of the links gradually and smoothly ride up on the flaring ends of the cross bar and the chain will therefore run smoothly and without jerks over the cross bar. The bottom portions of the links are also curved longitudinally, as shown, which enables the chain to make a sharper turn around the cross bar. The pivoted tongue k of the catch is also made from sheet metal and is bent by press operations, or in any other suitable way, into the shape shown, see Figs. 2—4. It has 10 hinge ears k^1 at opposite sides of its central portion which are pivoted to the opposite sides of the catch body by a rivet k^2 . One end of the tongue extends into engagement with the cross bar of the catch, and this end is preferably curved longitudinally and its 15 sides k^3 are folded or bent inwardly, as clearly shown in Figs. 2 and 3. A narrow but very stiff and strong beak is thus formed which will readily engage in and release the eyes of the chain links and withstand any strain to which it is subjected in use. The other end 20 k^4 of the tongue extends inside of and is adapted to bear against the extremity of the hook of the catch to close the opening between the hook and the sides of the catch and prevent the accidental disengagement of the hook from the hame loop. This flat end k^4 forms a 25 thumb piece for operating the tongue.

l represents the tongue operating spring, which consists of a strip of flat spring metal riveted at one end at l^1 to the central part of the tongue, between the hinge ears thereof, and bearing at its free end against the 30 hook-end of the catch body. The attached end of the spring is shaped to bear against the hinge ears and in-bent sides of the tongue and these coöperate with the securing rivet to rigidly hold the spring in place and to protect it from injury. The free portion of the 35 spring is located between and protected from injury by the sides of the catch body. The tongue spring is therefore almost completely hidden and is thoroughly

protected from injury, and as it extends from the central part of the tongue to the base of the catch hook, the hook can be readily engaged with the hame loop 50 by pressing the thumb piece of the tongue inwardly with the hame loop. The loop enters directly into the hook and does not have to be worked over the end of the spring to enter the hook as it would if the spring was secured to the end of the hook and bore against the thumb-piece of the tongue.

We claim as our invention:

1. In a fastener, the combination of a chain, and a catch for said chain comprising a body, a tongue for engaging the chain links provided with bent-over side portions pivoted to said body, and a tongue-operating spring consisting of a spring strip secured to said tongue between and bearing against said bent-over side portions and resting at its free end against said body, substantially as set forth. 60

2. In a fastener, the combination of a catch body having spaced sides connected by a back, a tongue provided with bent-over side portions pivoted to the sides of said body, and a tongue-operating spring consisting of a spring strip secured to said tongue between said bent-over side portions and bearing at its free end against the back of said body, said side portions of the tongue and sides of the body serving to confine and inclose said spring, substantially as set forth. 65

3. In a fastener, the combination of a chain, and a catch for said chain comprising a body, a tongue provided with side portions bent over to form hinge ears and a folded beak for engaging the chain links, and a tongue-operating spring consisting of a spring strip riveted at one end to the tongue between said bent-over side portions and bearing at its free end against said catch body, substantially as set forth. 75

4. In a hame fastener, the combination of a chain composed of links having relatively narrow deep loop ends and wide diverging eye-ends, a catch comprising a body provided with a cross bar over which said chain runs and which has flaring ends connected by a reduced waist portion, and a tongue for engaging the chain links, substantially as set forth. 80

5. In a hame fastener, the combination of a chain composed of links having relatively narrow deep loop ends and wide diverging eye-ends, a catch comprising a body provided with a cross bar over which said chain runs and which consists of a rivet and a surrounding sleeve having flaring ends connected by a reduced waist portion, and a tongue for engaging the chain links, substantially as set forth. 85

Witness our hands, this 17th day of May, 1906.
